(57) **CLAIM**

The ornamental design for side mirrors of an automotive vehicle, as shown and described.

DESCRIPTION

FIG. 1 is a front elevational view of side mirrors of an automotive vehicle showing our new design;

FIG. 2 is a rear elevational view thereof;

FIG. 3 is a right side elevational view thereof, a left side elevational view being a mirror image;

FIG. 4 is a partially enlarged front elevational view thereof along the lines 4-4 and 4'-4' of FIG. 1 showing a front elevational view of the right side mirror, while a partially enlarged front elevational view thereof showing the left side mirror being a mirror image;

FIG. 5 is a partially enlarged rear elevational view thereof along the lines 5-5 and 5'-5' of FIG. 2 showing a rear elevational view thereof showing a rear elevational view of the right side mirror, while a partially enlarged rear elevational view thereof showing a rear elevational view of the left side mirror being a mirror image;

FIG. 6 is a partially enlarged right side elevational view thereof along the lines 6-6 and 6'-6' of FIG. 3 showing a right side elevational view of the right side mirror, while a partially enlarged right side elevational view thereof showing a right side elevational view of the left side mirror being a mirror image;

FIG. 7 is a partially enlarged rear, right perspective view thereof along the lines 7-7 and 7'-7' of FIG. 3 showing a rear, right perspective view of the right side mirror, while a partially enlarged rear, right perspective view thereof showing a rear, left perspective view of the left side mirror being a mirror image; and,

(Continued)

FIG. 8 is a partially enlarged front, right perspective view thereof along the lines 8-8 and 8'-8' of FIG. 3 showing a front, right perspective view of the right side mirror, while a partially enlarged front, left perspective view thereof showing a front, left perspective view of the left side mirror being a mirror image.

The broken lines illustrate portions of the side mirrors of an automotive vehicle that forms no part of the claimed design.
